UNITED STATES PATENT OFFICE

GEORGE M. BARROW, OF DERRY, PENNSYLVANIA, ASSIGNOR TO WESTINGHOUSE ELECTRIC & MANUFACTURING COMPANY, A CORPORATION OF PENNSYLVANIA

INSULATOR

Application filed March 7, 1927. Serial No. 173,363.

My invention relates to insulators and particularly to insulators of the pin type.

One object of my invention is to provide an insulator, of the above-indicated character **5** that shall materially reduce losses in manufacture.

Another object of my invention is to provide an insulator that shall render more perfect certain parts which have heretofore been **10** unreliable in character.

A further object of my invention is to provide an insulator that shall be simple and desirable in construction, economical to manufacture and effective in its operation.

15 In the manufacture of porcelain insulators of the pin type, it has heretofore been usual to form the screw threads in the pin holes thereof by a reversing machine, either during or after the pressing operation which forms **20** the insulator proper, while the porcelain batch is in a plastic state. This operation usually requires the use of a relatively complicated and expensive machine. However, aside from the complication of the machine, **25** the forming of the screw threads directly in the main insulating body has the further objection that the threads frequently warp out of shape, during the firing of the insulator, so that relatively great losses occur in manu- **30** facture.

Warping of the threads is assisted by the firing of adjacent integral portions of different thickness or cross-sections, since the smaller or thinner sections tend to dry out **35** first and to leave a deleterious effect which is not so pronounced in portions of uniform or similar thickness.

In practicing my invention, I provide an insulator and a method of making the same, **40** whereby the screw threads, or similar holding portions, are formed separately from, or independently of, the main insulator body to eliminate the use of the above-mentioned reversing machine during manufacture and to **45** provide an insulator structure in which the above-mentioned objections are not present.

Figure 1 of the accompanying drawings is a side view, in longitudinal central section, of an insulator constructed in accordance with **50** my invention, and

Fig. 2 is a detail view of a modified portion thereof.

The insulator comprises, in general, an upper insulating member 2, a lower insulating member 3 having a recess 4 for the reception **55** of a pin or similar member for association with the insulator, and a holding element or sleeve 6 for cooperation with the pin.

The upper insulating member 2 comprises a surface-creepage petticoat 7, a tie-wire **60** groove 8, a groove 10 for the reception of a conductor to be supported by the insulator and a portion 11 of inverted substantially cup-shape that is cemented, or otherwise secured, to a head portion 12 of the lower insu- **65** lating member 3. The member 3 further comprises surface-creepage petticoats 14 and 15.

The above-described structure is merely il- **70** lustrative of an insulator for which my in- vention is adapted, since the upper member 2 may be an integral part of the member 3 or the device may comprise three or more parts similar to the parts 2 and 3. The sleeve 6, which has usually heretofore been constructed **75** as an integral or homogeneous part of the member 3, is, according to my invention, formed separately therefrom, either by a wet process or by a dry process, and secured in the member 3 in any one of several ways. **80**

A preferred method of making the sleeve **85** 6 is by the dry process in which the sleeve may be made single and homogeneous or in longitudinally divided half sections 17 and 18. The latter method has the advantage of rendering the operation a simple pressing operation and to render a reversing mold unnecessary. Such a reversing mold, or other relatively complicated and expensive means, is required where screw threads **90** are desired in the sleeve 6 and it is also desired to have the sleeve consist of one integral member. By longitudinally dividing the sleeve 6, it may be withdrawn laterally from the mold and placed together again for in- **95** sertion in the recess 4.

The sleeve 6 may be formed as a thimble, having its inner end 21 closed instead of open, as shown in Fig. 2. While the sleeve **100** 6 may be secured in position to advantage

by the use of metal alloy, molding composition or frangible cement, it is preferably insulatingly bonded to the member 3 by a frangible or refractory material, such as glaze or porcelain slip. In any case, the adjacent surfaces of the sleeve 6 and member 3 may be roughened, grooved, sanded or otherwise treated to ensure a more perfect bond.

10 Where porcelain slip or glaze is used as the bonding material, the member 3 and the sleeve 6 may be fired before the assembly thereof with the slip or glaze and again fired to vitrify the bonding material or all of the parts may be united before firing.

15 Since it is my main purpose to provide a refractory insulator having a refractory thread in the pin recess similar to, but more perfect than, insulators of this type heretofore employed and to retain certain other characteristics of the single homogeneous unit, the sleeve 6 is preferably united to the member 3 by glaze or slip. By this method, an insulator is provided that, while made up of separately fabricated parts, is substantially as homogeneous from an insulating standpoint and has more perfect threads than the prior art structures. By firing the member 3 and the sleeve 6 separately, or by 20 preforming them and assembling the same with glaze or slip therebetween before firing, warping of the sleeve is less likely to occur and losses from this cause are accordingly 25 materially reduced.

30 Also, by employing the dry-press process and longitudinally dividing the sleeve or thimble, a reversing mold is dispensed with and more perfect threads are ensured.

35 While I have shown and described particular forms of my invention, changes may be effected therein without departing from the spirit and scope thereof, as set forth in the appended claims.

I claim as my invention:

40 1. An insulator comprising a recessed insulating member and a longitudinally divided internally-screw-threaded insulating sleeve constituting a relatively thin lining for and compared to the thickness of the side walls thereof and bonded thereto in said recess.

45 2. An insulator comprising an insulating member having a pin recess and a longitudinally-divided insulating sleeve secured in position in said recess for holding co-operation with a pin removably associated with the insulator in said recess.

50 3. An insulator comprising a recessed insulating member and a longitudinally divided internally-screw-threaded element having a sleeve and a transverse wall constituting relatively thin linings bonded to the insulator in said recess.

55 4. An insulator comprising an insulating member having a pin recess and a longitudi-

nally-divided insulating element having a side-wall sleeve and an end-wall portion secured in position in said recess for holding co-operation with a pin removably associated with the insulator in said recess.

60 In testimony whereof, I have hereunto subscribed my name this 2 day of March 1927.

GEORGE M. BARROW.
